UNITED STATES PATENT OFFICE.

ROBERT L. RICHARDS, OF MERIDIAN, TEXAS.

PORTABLE BATHING APPARATUS.

1,272,715.

Specification of Letters Patent. Patented July 16, 1918.

Application filed November 30, 1917. Serial No. 204,552.

To all whom it may concern:

Be it known that I, ROBERT L. RICHARDS, a citizen of the United States, residing at Meridian, in the county of Bosque and State of Texas, have invented certain new and useful Improvements in Portable Bathing Apparatus, of which the following is a specification.

This invention pertains to improvements in bathing apparatuses.

The aim of this invention is to provide a portable apparatus which may be conveniently transported and which includes a water receptacle having means for heating the water therein to the desired temperature; together with a washing appliance receiving water from the receptacle through a flexible tube and having provision for holding and supplying water to a wash-cloth whereby one may wash his body.

This invention will be more readily understood from a reading of the following specification and by reference to the accompanying drawings, in which an example of the invention is illustrated and wherein:

Figure 1 is a perspective view of an apparatus constructed in accordance with this invention,

Fig. 2 is a plan view of the washer,
30 Fig. 3 is an inverted view of the same.

Fig. 4 is a longitudinal sectional view of the washer, showing back-handle inserted therein,

Fig. 5 is a transverse sectional view of
35 the washer,

Fig. 6 is a vertical sectional view of the heating receptacle, and

Fig. 7 is an underside view of said receptacle.

40 In the drawings the numeral 1 designates a receptacle having a flattened side 2 and an upstanding ear 3 at its top which is open. The flat side will rest against a wall and the ear may be engaged over a nail or the like to hold the receptacle at the desired elevation. Within the receptacle and above the lower edge a conical bottom 4 is disposed and merged into a central heating flue 5 extending to the top of the receptacle. Within the receptacle below the bottom a spring clip 6 is secured to the part 2 so as to receive and support a lamp 7 directly under the flue 5. The lamp is concealed and protected by the depending wall 55 of the receptacle and is readily removable.

Water placed in the receptacle surrounds

the parts 4 and 5 and is quickly heated. A nipple 8 extends from the receptacle immediately above the bottom 4 and receives the end of a flexible tube 9 of suitable structure. The other end of the tube is connected to the end of a nipple 10 projecting from the side of a device 11 for washing one's body, and which I have termed a "washer." A pressure cut-off device 12 is placed on 65 the tube and may be of any approved construction, there being many of these devices now in common use.

The washer includes a back 13 similar to the back of a clothes brush. This back has 70 an upstanding central hand-grip 14 which is provided with a longitudinal recess 15 adapted to receive a handle 16 like the usual back washing brushes now in common use. The back 13 fits in and closes a metal body 75 having parallel side walls 17 and an arculate face 18. At each side and each end the metal body is extended up and bent over the back and forked to form jaws 19. It will be noted that there are four jaws 80 and consequently a cloth, as A (Figs. 4 and 5) spread over the face and sides of the washer may have each corner engaged in a jaw and thus securely held and likewise easily removed when desired. 85

The nipple 10 is on the end of a perforated pipe 20 extending transversely within the washer and supplying water thereto. Transverse slots 21 are provided in the face 18 except at the central portion, the width 90 of the slots increasing successively from each side of the central portion. It is obvious that the slots supplying the water to the cloth the slots at the greatest distance from the pipe must be larger in order to 95 assure an even distribution. The tendency of the water will be to seek the lowest portion of the cloth and as this portion will be at the center of the face no slots will be required at this point. However this is not 100 a limiting feature and various arrangements of slots and openings could be made.

In using the apparatus the cut-off 12 is closed, the receptacle 1 is filled with water and the lamp 7 is lighted. A wash-cloth A 105 is spread over the sides 17 and face 18 of the washer 11 and its ends engaged in the jaws 19. After the water is heated to the desired temperature the cut-off 12 is opened permitting the heated water to pass through the tube 9 to the pipe 20 and thence through the slots 21 to the cloth A. The person

bathing may stand in a suitable receptacle (not shown). It is obvious that the cloth A will be saturated and by applying soap thereto or on one's body the operation of 5 bathing may be efficiently and conveniently performed. It is obvious that by dipping the washer in cold water the temperature of the bathing water may be cooled if desired and the supply of hot water can be 10 controlled by the cut-off 12. When it is desired to wash the back of the body the handle 16 may be used.

It is pointed out that the entire structure which has been described is extremely simple and thus makes for sanitary conditions 15 as all parts may be easily and thoroughly cleaned. The wash-cloth can be removed and replaced with a fresh one.

The foregoing description and illustration 20 clearly express the invention, but it is to be understood that said illustration is merely an exemplification and the inven-

tion may be carried out in various other ways.

What I claim, is:

1. In a body washer for bathing apparatuses, a back having an upstanding hand-grip, a hollow metal body receiving the back and comprising sides and an arcuate face, the face of the body having openings, 30 and the body having provision for admitting water, and jaws for holding the ends of a wash-cloth, said jaws being secured to the body member at spaced points and overhanging the back.

2. In a body washer for bathing apparatuses, a hollow body having an arcuate face provided with water outlets, a back fitting the body, wash cloth holding jaws comprising notched projections carried by the body 40 and overhanging the back, and means for supplying water to the metal body.

In testimony whereof I affix my signature.

ROBERT L. RICHARDS.
